(57) **CLAIM**

The ornamental design for a pet communication device, as shown and described.

DESCRIPTION

FIG. 1 is a perspective view of a pet communication device showing our new design;

FIG. 2 is a front view of the pet communication device.

FIG. 3 is a back view of the pet communication device.

FIG. 4 is a side view of the pet communication device.

FIG. 5 is a side view of the pet communication device.

FIG. 6 is a top view of the pet communication device; and,

FIG. 7 is a bottom view of the pet communication device.

The broken lines in the drawings depict environmental subject matter and do not form a part of the claimed design.
